UNITED STATES PATENT OFFICE.

RUDOLPH G. DRESSLER, OF NEW YORK, N. Y.

FLYING-MACHINE.

1,068,332.

Specification of Letters Patent.

Patented July 22, 1913.

Application filed March 25, 1909. Serial No. 485,589.

To all whom it may concern:

Be it known that I, RUDOLPH G. DRESSLER, a citizen of the United States, and a resident of the city of New York, Coney Island, borough of Brooklyn, in the county of Kings and State of New York, have invented a new and Improved Flying-Machine, of which the following is a full, clear, and exact description.

10 This invention relates to flying machines, and is of a type adapted to soar in a breeze and also adapted to raise itself by the flapping of wing members.

15 An object of the invention is to provide means whereby it can be started from the ground or from an elevated point such as a suspended trackway.

Another object of the invention is to provide means to assist in oscillating the wings.

20 A still further object of the invention is to provide improved steering means.

These and other objects will be more fully described hereinafter and particularly pointed out in the claims.

25 Reference is to be had to the accompanying drawings forming a part of this specification, in which similar characters of reference indicate corresponding parts in all the views, and in which—

30 Figure 1 is a perspective view of my device; Fig. 2 is an end elevation; Fig. 3 is an enlarged perspective view, showing the soaring planes in detail; and Fig. 4 is an edge view of the soaring planes.

35 Referring more particularly to the separate parts of the device, 1 indicates the base frame of the machine, which is composed of longitudinal members 2 and cross bars 3. Extending between the longitudinal members 2 are cross bars 4, which support a platform 5. The platform serves as a stand on which the navigator of the flying machine is supported.

40 On the outer extremity of the cross bars 3 are suitably journaled rollers 6, which are adapted to support the frame on the ground, so that it may be moved from place to place or pulled rapidly over the ground, in order to start the machine.

45 50 Extending from the ends of the frame 1 are upright supporting members 7, which may be of any suitable light material, such as bamboo or hollow steel. Intermediate the pairs of uprights 7 are placed uprights 8, which are of similar material to the uprights 7 and extend somewhat higher and

are converged toward each other, as at 9, to form a suitable support for a shaft 10, on which is rotatably mounted a starting roller or pulley 11. This roller 11 is for 60 the purpose of suspending the whole flying machine and frame from a suitable track when it is desired to start the device from an elevated position.

Extending longitudinally of the device 65 and alongside of the uprights 7 and 8 are longitudinal bars 12, which are connected together by means of tie-bars 13 and serve as pivots for wings 14, which extend on opposite sides of the frame. Extending longitudinally of the wings 14 are longitudinal bars 15, which serve as supports for bow-shaped cross bars 17. The latter extend at suitable intervals throughout the length of the wings and are adapted to support the 70 covered surface of the wings, which may be of any suitable material, such as oiled silk or the like, and are also adapted to support soaring planes 18 attached to the outer half of the wings. The soaring planes 75 are of peculiar structure, in that they are substantially rigid for three-quarters of their length, and for the remaining quarter are flexible, so that they may be bent up and down above and below the plane of the 80 wing, this bending being accomplished by the action of the wing oscillating up and down through the air, and the direction of the bending of these soaring planes will be just the reverse of the direction in which 85 the wings are oscillated; that is to say, when the wing is sweeping downward, the rear quarter of the soaring plane will be bent up by the force of the air rushing against its 90 under surface. The soaring planes are connected to the cross bars 17 by means of flexible cords or chains 16, which are secured to the soaring plane at about the beginning of its flexible portion. The wings 14 have a 95 slight slope or grade to the rear, of about 100 2%. This enables the wings to exert a lifting action to the whole frame when a breeze of ten miles or over comes against their under surface. At the same time, the rear edges of the soaring planes will be bent up 105 by this breeze and will exert a forward push on the machine.

Connected to the under side of the wings and to the longitudinal bars 15 are connecting links 19 which converge together and 110 are fastened to a suitable combined hand-and-foot operating lever 20, which is

adapted to be engaged by the operator, who stands on the platform 5, to oscillate the wings up and down. The operator is assisted in this oscillation on the downward stroke by means of springs 21, which are fastened to the under side of the wings and also to the upright members 8 of the frame.

As clearly shown in Fig. 2, the wings are spaced apart, and have projecting directly over the space between them an aeroplane or supporting plane 22, which is connected to and supported by the uprights 7 and 8. This plane 22 has a rearward slope similar to the slope of the wings 14, but of a slightly greater degree, so that the wings and the plane converge toward each other. The direction of the plane 22 is similar to that of the wings, in that the outer ends of the plane have soaring planes 23 similar to those described on the wings, which are also adapted to have both a lifting and a forward propelling action. The soaring planes 23 extend for over two-thirds of the width of the aeroplane, and are supported at their ends by longitudinal bars 24. These soaring planes, similar to the soaring planes on the wings, are connected to the adjacent cross bar by means of a flexible connecting cord or chain 25.

The two rear upright supports 7 are connected about midway of their height by a cross bar 26, which has a bearing 27 therein, in which is rotatably supported a shaft 28, which is also supported at some distance away from the frame by a bearing 29 connected to the uprights 7 and the frame 1 by means of an auxiliary frame, which is composed of the converging brace rods 30.

On the outer end of the shaft 28 and secured thereto is a steering means, which consists of horizontal triangular planes 31, the side edges of which converge toward each other and to the under surface of which is secured a vertical triangular plane 32, the edge of which also slopes toward the converging point of the other triangular planes. Connected to the other end of the shaft 28 is a suitable steering hand-wheel 33, which is adapted to manipulate the planes 31 and 32, so as to direct the flight of the machine.

In the operation of the device, if there is no wind blowing and it is desired to start the machine from an elevation, it is suspended by means of the roller 11, from an inclined trackway, and allowed to run down until a sufficient momentum has been obtained by the machine to create a lifting force on the surfaces of the wings and supporting plane 22. When the machine tends to fall after leaving the supporting rail, the rear ends of the soaring planes are bent up, and the air, being compressed beneath them, tends to force them forward, and thus forces the whole flying machine forward. The operator who stands on the platform 5, may

add any force necessary to keep the flying machine in flight by means of the combined hand-and-foot lever 20, which is adapted to reciprocate the wings 14, he being aided in the downward stroke by the springs 21, the weight of the machine itself being sufficient to return the wings to their upper position. If there is sufficient wind blowing, it is not necessary to start the machine from an elevated point, but it may be started from the ground. The wind blowing against the inclined surfaces of the wings and plane 22 exerts a lifting force thereon, and thus lifts the whole machine from the ground. The operator may also aid in this case by flapping the wings. In the downward stroke of the wings, the rear ends of the soaring planes are bent upward, and the air is compressed under this flexible portion and serves to create an upward force thereon, tending to force the planes in a forward direction and thus force the whole machine forward. On the up-stroke of the wings, the flexible rear ends of the soaring planes are bent downward, and again the pressure of air tends to force the planes forward in a manner similar to that obtained in the downward stroke of the wings. If the air, either when the machine is traveling forward or when the wind is traveling against the machine, comes against the inclined surfaces of the wings and aeroplane, it tends to be compressed until it comes under a flexible portion of the soaring planes, where it creates the forward propulsion, as described above.

Any suitable motor means may be substituted for the combined hand-and-foot lever 20 to operate the wings, thus leaving the operator's hands free to start the motor and manipulate the steering plane.

Having thus described my invention, I claim as new and desire to secure by Letters Patent:—

1. In a flying machine, the combination with an upright frame, of oscillating wings pivoted to the sides of the frame, said wings being spaced apart and having flexible planes thereon which are adapted to oscillate simultaneously in a direction opposite to that in which the wings oscillate.

2. In a flying machine, the combination with a vertical supporting frame, of inclined wings pivoted to the sides of said frame, and an inclined aeroplane fixed to said frame, said wings and said aeroplane having soaring planes, part of the surfaces of which are adapted to oscillate in a direction opposite to the direction in which the wings and aeroplane move.

3. In a flying machine, the combination with a vertical supporting frame, of inclined wings pivoted to the sides of said frame, said wings being spaced apart, and an inclined aeroplane fixed to said frame and situated above the space between said wings,

said wings and said aeroplane having soaring planes, part of the surfaces of which are adapted to oscillate simultaneously in a direction opposite to the direction in which the 5 wings and planes are moving.

4. In a flying machine, the combination with a vertical supporting frame, of wings pivoted to said frame, and steering means comprising a horizontal plane and a vertical 10 plane extending wholly below the surface of the horizontal plane.

5. In a flying machine, the combination with a vertical supporting frame, of wings pivoted to said frame, and steering means 15 comprising a horizontal triangular plane, and a vertical triangular plane extending wholly below the surface of the horizontal plane.

6. In a flying machine, the combination 20 with a vertical supporting frame, of supporting planes for said frame, and steering means comprising a triangular plane and another triangular plane extending at an angle to the first-triangular plane on one 25 side thereof.

7. In a flying machine, the combination with an upright supporting frame, of supporting planes carried by said frame, an auxiliary frame connected to said first-mentioned frame; a shaft pivoted in bearings on said frame, a plurality of planes having converging side edges secured to one end of said shaft, and a hand wheel secured to the other end of said shaft.

35 8. In a flying machine, the combination with a frame, of wings secured to said frame, and an aeroplane secured to said frame, said wings and said aeroplane sloping downward toward the rear, and the slope of said aeroplane being slightly greater than that of the 40 wings.

9. In a flying machine, the combination with a frame, of sloping wings supported on said frame, and a sloping aeroplane for said 45 frame, said wings and said aeroplane converging toward each other.

10. In a flying machine, the combination with a vertical supporting frame, rollers connected to the base of said frame, a supporting roller connected to the top of said frame

and adapted to support said frame from an inclined track, wings pivoted to the opposite sides of said frame and being spaced apart, soaring planes on said wings, having part of their surfaces flexible; an aeroplane 55 situated above the space between said wings and connected to the frame, soaring planes on said aeroplane, said soaring planes having flexible portions adapted to oscillate to positions on opposite sides of said aeroplane, 60 and steering means connected to said frame comprising triangular planes, the side edges of which converge toward each other.

11. In a flying machine, a frame comprising longitudinal members and cross bars, 65 rollers connected to said cross bars and adapted to support said frame, vertically-extending uprights connected to the ends of said frame, intermediate uprights extending from said frame, said intermediate uprights 70 converging toward each other at the top, a roller rotatably supported in said converging uprights, arched wings pivoted to each side of said uprights, cross bars on said wings, soaring planes secured to said cross 75 bars and having a portion of their surfaces flexible so that they may oscillate up and down above and below the plane of the wings, connecting links secured to the under side of said wings, a lever connected to said 80 links and adapted to operate said wings, a spring secured to the side of said converging uprights and adapted to assist in a downward stroke of said wings, an aeroplane situated above said wings and sloping downwardly toward the rear, flexible soaring planes on said aeroplane, an auxiliary frame connected to the upright supports, a shaft rotatably supported in said auxiliary plane, 85 triangular planes, having their edges converging toward each other, secured to said shaft, and a hand-wheel for operating said shaft.

In testimony whereof I have signed my name to this specification in the presence of 95 two subscribing witnesses.
